United States Patent Office

Des. 179,687
Patented Feb. 12, 1957

179,687

TRAY CART

Axel E. F. Johnson, Cincinnati, Ohio, assignor to Meal-pack Corporation, Evanston, Ill., a corporation of Illinois

Application May 7, 1956, Serial No. 41,365

Term of patent 14 years

(Cl. D14—3)

Fig.1

Fig.2

Fig.3

Fig. 1 is a perspective view of a tray cart showing my new design;

Fig. 2 is a perspective view similar to Fig. 1 but showing the opposite end of the cart;

Fig. 3 is a top plan view;

Fig. 4 is a side elevational view;

Fig. 5 is a front elevational view; and

Fig. 6 is a rear elevational view.

I claim:

The ornamental design for a tray cart, as shown.
